(57) **CLAIM**

The ornamental design for a housing for a pallet tracking device as shown and described.

DESCRIPTION

FIG. 1 is a front view of a housing for a pallet tracking device in an open state showing our new design;

FIG. 2 is a front view in a closed state thereof;

FIG. 3 is a left side view in an open state thereof;

FIG. 4 is a left side view in a closed state thereof;

FIG. 5 is a right side view in an open state thereof;

FIG. 6 is a right side view in a closed state thereof;

FIG. 7 is a rear view in a closed state thereof;

FIG. 8 is a rear view in an open state thereof;

FIG. 9 is a top view thereof;

FIG. 10 is a bottom view thereof;

FIG. 11 is a perspective view in an open state thereof; and,
FIG. 12 is a perspective view in a closed state thereof.

The broken line elements inside the outermost rounded square in FIG. 10 form no part of the claimed design.

1 Claim, 12 Drawing Sheets
